UNITED STATES PATENT OFFICE

172,814

FISH LURE

Earl J. Bayerl, Pierz, Minn.

Application December 17, 1953, Serial No. 28,113

Term of patent 14 years

(Cl. D31—4)

To all whom it may concern:

Be it known, that I, Earl J. Bayerl, a citizen of the United States, residing at Pierz, county of Morrison, and State of Minnesota, have invented a new, original, and ornamental Design for a Fish Lure, of which the following is a specification, reference being had to the accompanying drawing, forming a part thereof.

Figure 1 is a top view of a fish lure showing my new design;

Figure 2 is a side view of the lure;

Figure 3 is a rear view thereof; and

Figure 4 is a front view of the lure.

I claim:

The ornamental design for a fish lure, substantially as shown.
